(57) **CLAIM**

The ornamental design for a fishing rod holder with integral beverage holder, as shown and described.

DESCRIPTION

FIG. 1 is a front view of a fishing rod holder with integral beverage holder in accordance with the present invention;

FIG. 2 is a rear view thereof;

FIG. 3 is a side view thereof;

FIG. 4 is a top view thereof; and,

FIG. 5 is a bottom view thereof.

The broken lines shown in the various Figures are shown for illustrative purposes only and form no part of the claimed design.
